UNITED STATES PATENT OFFICE.

ARTHUR S. LITTLEFIELD, OF WINNETKA, ILLINOIS, ASSIGNOR TO LITTLEFIELD MANUFACTURING COMPANY, OF CHICAGO, ILLINOIS, A CORPORATION OF ILLINOIS.

TOY CANNON.

Application filed July 11, 1927. Serial No. 204,750.

This invention relates to improvements in what are commonly termed "toy cannons" such as are used in connection with games of the war or battle type and has for its object to provide a magazine gun of this type and projectiles therefor possessing certain advantageous characteristics designed to cooperate to prevent jamming of the gun or its magazine by reason of projectiles becoming canted therein.

A very essential object of the present invention resides in the details of construction of the magazine of the gun whereby the same is formed up and completed simultaneously with effecting its rigid association with the gun barrel.

The invention, in its preferred embodiment, is fully illustrated in the accompanying drawings, wherein:

20 Figure 1 is a central vertical longitudinal section of a magazine gun constructed in accordance with the invention.

Figure 2 is a similar view showing the gun plunger drawn back preparatory to release thereof to eject a projectile.

25 Figure 3 is a fragmentary top plan view of the gun and its magazine.

Figures 4 and 5 are vertical transverse sections on the lines 4-4 and 5-5 respectively, of Figure 1.

30 Figure 6 is a perspective view of a projectile for the gun.

Figure 7 is a plan view of a sheet metal blank of which the magazine is made.

35 The gun comprises the barrel 1 having a cylindrical bore 2 closed at one end by means of the breech-block 3 which may be composed of wood, cork or other material, the gun barrel being preferably made of wood.

40 In the breech-block 3 is a central opening axially coincident with the bore 2 and through which one end portion of the plunger 4 passes freely, said plunger being provided between its ends with an annular enlargement 5 substantially fitting the bore 2.

45 A helical compression spring 6 is interposed between the portion 5 of the plunger and the breech-block 3. The outer end of the plunger 4 is equipped with a handle element 7 which is cylindrical and is provided between its ends with an annular groove 8 to permit

the same to be easily digitally engaged for drawing back against the action of the spring 6 as shown in Figure 2. The outer end of the plunger 4 enters a central bore in the element 5 and is preferably secured to the latter by means of the key-pin 9.

The gun barrel 1 is provided between its ends in the uppermost portion of its circumferential wall with a longitudinal slot 10 through which the projectiles 11 enter the bore 2. Fitted to the barrel 1 is a tubular magazine 11 made preferably of sheet metal and which is of rectangular cross-section, the lateral and longitudinal dimensions 65 of said magazine 11 being such that the lower ends of the end walls thereof fit snugly telescopically within the slot 10 at the ends of the latter. The side walls of said member 11 are provided midway between their 70 side edges with longitudinal indentations forming ribs 12 interiorly of the tube 11, the lower ends of said ribs providing projections 13 which extend into the slot 10.

The said magazine member is composed of 75 a single piece of sheet metal which, as shown in Figure 7, illustrating the blank before forming, comprises two side wall portions 14 and 15 respectively, connected with each other by intermediate strap-portions 16 80 spaced from each other by the longitudinal slot 17. The portion 14 is of such greater width than the portion 15 as to include the end-wall portions 18 adapted to be bent at right angles to the middle portion thereof 85 along the dotted lines 19. At the side edges of the portion 14 are two pairs of lugs or flanges 20 and at the side edges of the portion 15 is one pair of lugs or flanges 21 all of said lugs or flanges being bent to extend 90

at right angles to the adjoining side edge portions of said portions 14 and 15 of the blank after the latter is bent to cause the said portions to become opposed to each other to form the tube 11, the lugs or flanges 95 20 then overlapping the outer faces of the portion 15 and the lugs or flanges 21 then overlapping the end wall portions of the portion 14 of said blank to thereby securely lock the walls of the tube 11 against relative displacement. It will be understood, 100 of course, that the rib formations are pro-

vided before the tube is formed and that the strap portions 16 are severed from the extreme inner end portions of the end walls of the tube 11.

- 5 The tube 11 is formed after the ribs 12 have been formed and the end wall portions of the portion 14 bent to extend perpendicularly to the said portions 14. The gun barrel 1 is then disposed upon the strap-
10 portions 16 which are formed about said barrel as the portions 14 and 15 are brought into parallel opposed relation and the projections 13 and extreme lower ends of the end-walls are sprung into the slot 10 of the
15 barrel. The several lugs or flanges 20 and 21 are then bent as above described to complete the magazine tube 11 and, at the same time, secure the same rigidly to the gun barrel. The latter is provided with an annular
20 shallow groove to receive the said strap-portions 16, the outer side edges of which engage the annular shoulders at the ends of said grooves to prevent longitudinal movement of the magazine relatively to the gun barrel.
25 At the upper ends of the ribs 12 I provide indentations which form opposed projections 25 spaced from each other a distance slightly less than the diameter of the middle or annular groove portions 24 of the cylindrical projectiles 25, the end portions of which are of a diameter slightly less than that of the bore 2 of the gun barrel 1, the total length of each projectile being somewhat less than the longer diameter of the
30 magazine 11, the ribs 12 of the latter preventing the ends of the projectiles from coming into contact with the end walls of the magazine to thereby more effectually prevent canting of said projectiles.
35 The operation of the device will be very readily understood without further description.

I claim as my invention:

1. The combination with a gun barrel
40 having a longitudinal slot between its ends, of a magazine tube mounted on said barrel and communicating at its discharge end with said slot, inwardly extending guide formations on opposed walls of said tube, and projectiles provided with guide formations between their ends for cooperation with the formations of said tube to prevent canting of said projectiles.
45 2. A magazine tube for the purpose specified, rectangular in cross-section, opposed walls of said tube provided with longitudinal guide formations, and projectiles provided between their ends with cooperating guide formations adapted to cooperate with the formations of said tube to prevent canting of said projectiles.
50 3. In a toy gun, the combination with a rectangular magazine tube having guide formations on opposed walls thereof, of projectiles of less length than a diameter of
55

said tube parallel with the walls thereof having said formations, and formations on said projectiles adapted to cooperate with the formations of said tube to prevent contact of the ends of the projectile with the other walls of said tube.

4. A magazine gun comprising a gun barrel having a longitudinal slot between its ends, a rectangular tube having formations at one end engaging in said slot, and metallic hoops secured to the lower ends of the tube and embracing the gun barrel for securing said tube thereto.

5. A magazine gun comprising a gun barrel having a longitudinal slot between its ends, a rectangular tube having formations at one end engaging in said slot, and metallic hoops integral with the side walls of said tube and embracing the gun barrel for securing said tube to the latter.

6. A magazine gun comprising a gun-barrel having an annular groove between its ends and a longitudinal slot having its end walls flush with the end walls of said groove, and a rectangular tube mounted to register at one end with said slot, and metallic hoops engaging in said groove and attached to the discharge end of said tube for securing the latter to the barrel.

7. A magazine gun comprising a gun barrel having an annular groove between its ends and a longitudinal slot having its end walls flush with the end walls of said groove, and a rectangular tube mounted to register at one end with said slot, and metallic hoops engaging in said groove and attached to the discharge end of said tube for securing the latter to the barrel, said tube provided at its discharge end with formations engaging in said slot for cooperation with said hoops to maintain said tube in position on said barrel.

8. The combination with a gun barrel having a longitudinal slot between its ends of a magazine member comprising a pair of parallel opposed side wall portions provided with interengaging side edge portions cooperating with said side wall portions to form end walls of a rectangular tube and interlock said side wall portions against relative movement, and strap elements integral with said side wall portions and forming hoops embracing the gun barrel at the slot portion thereof for maintaining said tube positioned to communicate with said slot.

9. A magazine gun comprising a gun barrel having an annular groove between its ends and a longitudinal slot having its end walls flush with the end walls of said groove, a magazine member comprising a pair of parallel opposed side wall portions provided with interengaging side edge portions cooperating with said side wall portions to form end walls of a rectangular tube and interlock said side wall portions against relative movement, and strap elements integral

with said side wall portions and forming hoops embracing the gun barrel within said groove.

10. The combination with a gun barrel having a longitudinal slot between its ends of a magazine member comprising a pair of parallel opposed side wall portions provided with interengaging side edge portions cooperating with said side wall portions to

10 form end walls of a rectangular tube and in-

terlock said side wall portions against relative movement, and strap elements integral with said side wall portions and forming hoops embracing the gun barrel at the slot portion thereof for maintaining said tube 15 positioned to communicate with said slot and projections at the lower ends of walls of said tube engaging in said slot for co-operation with said strap elements.

ARTHUR S. LITTLEFIELD.
